US0D1036432S

(12) **United States Design Patent** (10) **Patent No.:** **US D1,036,432 S**
(45) **Date of Patent:** **** Jul. 23, 2024**

(54) **TABLET COMPUTER**

(71) Applicant: **HMD Global Oy**, Espoo (FI)
(72) Inventor: **Miika Johannes Mahonen**, Espoo (FI)
(73) Assignee: **HMD Global Oy**, Espoo (FI)
(**) Term: **15 Years**
(21) Appl. No.: **29/811,428**
(22) Filed: **Oct. 14, 2021**

(30) **Foreign Application Priority Data**

Apr. 16, 2021 (EM) 008506182-0001
(51) **LOC (14) Cl.** **14-02**

(57) **CLAIM**

The ornamental design for a tablet computer, as shown and described.

DESCRIPTION

FIG. 1 is a front perspective view of a tablet computer showing my design.

FIG. 2 is a rear perspective view of the tablet computer in FIG. 1.

FIG. 3 is a front elevation view of the tablet computer in FIG. 1.

FIG. 4 is a rear elevation view of the tablet computer in FIG. 1.

FIG. 5 is a left side elevation view of the tablet computer in FIG. 1.

FIG. 6 is a right side elevation view of the tablet computer in FIG. 1.

FIG. 7 is a top plan view of the tablet computer in FIG. 1; and,

FIG. 8 is a bottom plan view of the tablet computer in FIG. 1.

The broken lines in the drawings show portions of the tablet computer and form no part of the claimed design.

1 Claim, 8 Drawing Sheets
